UNITED STATES PATENT OFFICE.

ARTHUR L. BREITENSTEIN, OF AKRON, OHIO, ASSIGNOR TO THE EAST PALESTINE RUBBER COMPANY, OF EAST PALESTINE, OHIO, A CORPORATION OF OHIO.

DESIGN FOR A VEHICLE-TIRE.

51,746.

Specification for Design.

Patented Feb. 5, 1918.

Application filed November 8, 1917. Serial No. 200,981. Term of patent 14 years.

To all whom it may concern:

Be it known that I, ARTHUR L. BREITENSTEIN, a citizen of the United States, residing at Akron, in the county of Summit and State of Ohio, have invented a new, original, and ornamental Design for Vehicle-Tires, of which the following is a specification, reference being had to the accompanying drawing, forming a part thereof.

Figure 1 is a face view of a portion of a vehicle tire, showing my new design.

Fig. 2 is a section on the line II—II of Fig. 1.

I claim:

The ornamental design for a vehicle tire, substantially as shown.

ARTHUR L. BREITENSTEIN.
